UNITED STATES PATENT OFFICE.

WILHELM EBERHARD ERNST, OF BERLIN-SCHONEBERG, GERMANY.

DEVICE FOR THE IMPROVEMENT OF THE MIXTURE IN INTERNAL-COMBUSTION ENGINES.

Application filed August 27, 1924, Serial No. 734,533, and in Germany March 13, 1923.

The vaporizing work of the carburettor remains preserved only partly up to the suction valve. Part of the vaporized mixture precipitates on the travel through the suc-

6
tion pipe, this being especially perceptible when heavy fuels are used. It has been proposed to suppress the suction pipe by connecting with each motor block or even with each cylinder a separate carburettor
10 directly or through the intermediary of a short tubular socket. The mixture arrived however nevertheless in the valve chamber in moist state and inclining to condensation.

14 It has been further proposed to make the suction pipe fork-shaped and to re-unite the branches in the cylinders in order to produce an eddying, but this has also been unsuc-
cessful.

If combustible mixtures have to combust
20 entirely in the cylinder, fuel particles and oxygen particles must be in the finest possible distribution and in the most favorable arrangement to one another. This condition is realized, especially for fuels of higher
25 viscosity, neither in the carburettor nor in suction pipes even if they are constructed in such a manner that the formation of eddies in the mixture (jet air) is ensured. So long as the rate of flow of the mixture is
30 greater than that of the diffusion merely a thread-like arrangement of the oxygen- and fuel particles is obtained.

Eddies produced shortly before the suction valve or in the valve chamber are capable of producing a better distribution of the fuel drops in the air but also in this case the thread-like arrangement remains as eddying threads propagating in the flow.

35 A very high degree of the desired molecular distribution of the mixture is attained if, according to the invention, one or several pairs of mixture streams produced at a point where mixing takes place, for instance in the carburettor, are conducted at increased
40 rate of flow through nozzles into a mixing chamber so that the individual streams of each pair strike violently on one another. According to the angle of incidence selected, to the distance between the nozzles and the
45 rate of flow due to the shape of the nozzles, clearly defined penetration zones are obtained. In this case there are no longer layers of streams or threads which whirl the one around the other, but—according to
50 the perfection of arrangement—an instant-

taneous positive diffusion is obtained in which the oxygen particles and the fuel particles are brought into an extraordinarily favorable mutual position.

The more uniform the distribution of the
60 fuel is the more can the temperature of the mixture be reduced without danger of separation. This means the advantage of a greater weight of the charge.

The individual streams of mixture may come from a common point at which the mixture is formed, the mixture being subdivided during the travel to the cylinder to be re-united again in the mixing chamber, or several streams coming each from a
70 separate point at which a mixture is formed may be conducted so that they strike violently on one another in the mixing chamber.

Nozzles, slits or other means are inter-
75 posed preferably between the point where the mixture is formed and the mixing chamber, whereby an increased velocity is im-
parted to the several streams before they enter the mixing chamber. These nozzles,
80 slits or other means are rendered adjustable
in order that the cross section, the direction
of the streams and the distance of the points
where they enter into the mixing chamber
85 may be altered and regulated singly or si-
multaneously.

An especially favorable embodiment of the invention is illustrated in the accom-
panying drawings, the mixing space pos-
sessing an especially favorable shape. The
invention is however not limited to the form
90 of construction shown but comprises all ar-
rangements and means which are adapted
to make streams strike violently on one an-
other between the points where the forma-
tion of mixture takes place and the inner
95 space of the cylinder, so that a thorough
working of the streams and consequently an
improvement of the evaporation- and gasifi-
cation state is produced.

In the accompanying drawings:—

Fig. 1 shows in elevation diagrammatically a cylinder block with an arrangement of the device according to the invention given by way of example.

Fig. 2 is an enlarged longitudinal section
100 through the device.

Fig. 3 shows in elevation part of the de-
vice in another position than that in Fig. 2.

Fig. 4 is a cross section on line IV—IV
110 of Fig. 3.

Fig. 5 shows a constructional detail in elevation.

Fig. 6 shows the element illustrated in Fig. 4 in longitudinal section in the position of the narrowest opening.

In the mixing device according to the invention, mixing casings 3 are arranged between a point 1, where the formation of the mixture takes place, and the engine cylinder, 10 and preferably in immediate proximity to the conduits in the cylinder block, which lead into the combustion chambers. Each casing 3 contains a mixing chamber 2 and is connected with a mixing tube or intake manifold 4 leading from the point 1 where the formation of the mixture takes place. In the casing, a seat 5 for a rotary sliding valve 10 is arranged, and is provided with windows 6, an annular space 7 being provided between the inner surface of the casing and the outer surface of the seat 5. The seat 5 is preferably of conical shape for reasons which will be hereinafter explained and it has a bearing face 8 which is in contact with the cylinder block and adapted to be adjusted. With this object in view, incisions 9 are arranged in the lower end of seat 5 designed to receive a key for rotating the seat so that the position of the windows 6 relatively to the casing 3 may be varied. The mixing tube 4 is preferably connected with the casing 3 so that it terminates eccentrically in the annular space 7 as indicated in Fig. 1. The seat 5 is mounted in 35 the casing 3 so that the mixture coming from the mixing tube must divide before it can flow through the windows or ports 6 into the mixing chamber 2.

In the seat 5, a rotary slide valve 10 with 40 ports 11 is arranged, which may be rotated according to requirement to regulate the inflow of the mixture from the mixing tube or from the annular chamber 7 into the mixing space 2. The mixing space 2 which is 45 formed of the inner space of the rotary slide valve 10 and of the adjacent part of the seat 5 has such a shape that the cross sections become larger in the direction of flow. For this reason in the form of construction illustrated, a conical shape of the rotary slide valve and of the seat has been selected.

The edges 12 of the windows of the seat 5 and the edges 13 of the windows of the rotary slide valve 10 are preferably arranged 55 so that at the beginning of the opening only quite narrow cross sections are liberated on the base of the gradually enlarging mixing space 2 and so that the streams admitted into the mixing chamber penetrate the one into 60 the other in equal distance from the base of the mixing space and without considerable formation of eddies approximately in the central longitudinal axis of the mixing space, in order to develop gradually without coming essentially in contact with the

wall of the mixing space, whereby a prejudicial friction or condensation of the mixture might be produced (see Fig. 6).

From Figure 6 it may be seen that thin streams of the mixture mix with one another 70 in a space at the narrowest cross section, but streams of greater cross section mix, for instance at an opening, as shown in Fig. 3.

While the degree of opening is determined 75 by the shape of the opening edges 12 or 13 in the form of construction shown by the curvature of the edge 13 along the line 13^a, the conducting of the mixture along the central longitudinal axis of the mixing 80 space is due to the special construction of the boundary faces of the ports 6 and 11. Experiments have shown that a similar effect is not produced, as could be assumed, by boundary faces directed towards the central longitudinal axis but that the boundary faces must preferably be undercut with regard to the radial direction and that further opening edges 12 and 13 which are sharp 85 like knife edges are especially advantageous 90 (compare in Fig. 4 the angles α and β) of which the boundary faces are undercut with regard to the radial direction. The flowing of the mixture over the sharp edges exerts further a very favorable influence on the intensive vaporization of the mixture. It is 95 advantageous that even at complete opening, the sharp edges of the rotary slide valve is not completely covered by the seat.

It is advantageous if the central axis of 100 the mixing space coincides with the axis of the bore of the mixture inlet a in the cylinder block b so that the inflow of the mixture into the valve space of the working cylinder 105 takes place without any essential change of direction. The distance from the base of the mixing chamber to the inflow point on the valve is preferably of such a length that a sufficient building up of the mixture cone ascending from the mixing space has already 110 taken place before the mixture passes through the valves. Owing to the direct contact of the seat with the cylinder block 115 the heat from the cylinder block, is transferred to the wall of the mixing space. 115

The rotary slide valve 10 has a stud 14 on which a spring 15 is mounted, designed to ensure the tight contact between the rotary slide valve and the seat 5 against the sucking effect of the piston. This stud 14 120 carries further a lever 16. The levers of several of such devices may be connected with one another by a link 17 and they may further be connected by a rod system 18 with a lever (not shown) arranged on the driver's 125 seat. A screw 19 which engages with a groove 20 of the stud 14 serves to limit the rotation of the slide valve. The stud 14 may further have a longitudinal bore 21 through which an additional mixture com- 130

ponent, air, liquid fuel or the like, may be added in the mixing space (see Fig. 5). A rotary slide valve of the arrangement described is distinguished by easy movements and tight contact.

The device may be connected directly with the point where the formation of mixture takes place (carburettor) and take over entirely or partly the function of the 10 throttling flap of the carburettor. The longitudinal axis of the carburettor and of the device may coincide.

The device is evidently not only designed for internal combustion engines in which the 15 admission of the mixture into the cylinder takes place under the action of the vacuum in the cylinder but it may be used also in connection with engines in which the admission of the mixture into the cylinder takes 20 place under additional pressure (compressor motors, mixture machines with mixtures produced by injection under pressure and the like).

The mixing process as it is effected by a 25 device similar to that described represents the last decisive step of preparing the mixture and evaporation but it shall not be excluded that according to the prevailing conditions a certain acceleration of mixture 30 be produced behind the mixing point for instance by a shape of the nozzle which does not reduce the charging degree.

I claim:

1. A fuel mixing device adapted to be 35 placed between the intake of an internal combustion engine and the point at which the fuel mixture is formed comprising in combination a casing provided with a fuel inlet and outlet, partition walls in the casing for sub-dividing the fuel mixture into a plurality of streams, a mixing chamber associated with the casing and widened in the direction of flow of the mixture, closure members between the casing inlet and the 40 mixing chamber for directing the sub-

divided streams of fuel into the mixing chamber and permitting the streams to contact with each other according to their cross section, whereby streams with smaller cross section at short distances will mix with 50 those of larger cross section at substantially greater distances.

2. A mixing device as claimed in claim 1 including curved closure edges on the closure members leaving only a small cross section 55 on slight opening angle of the closure member, said cross section greatly increasing with further opening.

3. A mixing device as claimed in claim 1 including curved sharp breaking edges on 60 the closure edges, leaving only a small cross section at slight opening angle of the closure member, said cross section greatly increasing on further opening.

4. A mixing device as claimed in claim 1 65 including curved sharp cutting edges at certain points on the closure members.

5. A fuel mixing device adapted to be placed between the intake of an internal combustion engine and the point at which 70 the fuel mixture is formed comprising a circular casing having an inlet arranged to discharge a fuel mixture tangentially into said casing, a conical seat arranged in the casing and provided with oppositely disposed windows, a rotatable valve arranged in the seat and having openings adapted to 75 cooperate with the windows in the seat for admitting streams of fuel into the interior of the valve at opposite points, the interior of said valve forming a conical mixing chamber widening in the direction of the flow of the mixture.

6. A mixing device as claimed in claim 5 in which the seat has an annular bearing 80 surface and is rotatably mounted in the casing.

In testimony whereof I affix my signature.

WILHELM EBERHARD ERNST.
